SPRAYING DEVICE

David A. Spriggs, Bloomfield, N. J., assignor to
 Standard Container, Inc., Bloomfield, N. J., a
 corporation of New Jersey

Application March 26, 1938, Serial No. 198,162

9 Claims (Cl. 299—88)

This invention relates to an improvement in spraying devices of the character used for the distribution of liquid insecticides or other liquids, and particularly to a type of sprayer combined with, or built in, an insecticide can or similar receptacle, an example of such a structure being disclosed in the co-pending application of William Martin Vogel, Serial No. 182,156, filed December 28th, 1937.

10 The present invention has for its object the provision of a built-in sprayer of the character described by which the contents of the can may be sprayed directly from the can; which does not interfere with the normal use of the can 15 whereby when desired the contents may be poured out in the conventional manner; which will prevent wastage of the liquid contents of the can and provide other advantages hereinafter pointed out.

20 In the accompanying drawing, wherein an embodiment of the invention is shown, Fig. 1 is a sectional view through a combined can and sprayer made in accordance with the invention; Fig. 2 is an enlarged sectional view through the liquid supply opening in the top of the can, showing the spout and closure cap; and Fig. 3 is a sectional view on the line 3—3 of Fig. 1, looking in the direction of the arrows.

With reference to the structure shown in Fig. 30 1, the body of a can or similar receptacle is shown at 1, and the same may be of any suitable form and size convenient to be held in one hand, while the built-in sprayer is operated with the other hand. A can of approximately quart 35 size has been found convenient. In the form shown, the body of the can is substantially rectangular in cross-sectional shape. Seamed to the upper end of the body 1 in the conventional manner is the top 2 and similarly secured to the lower end of the body is the bottom 3. Extending through the body of the can from top to bottom thereof is a tube 4. Said tube is normally open at the top and bottom and does not communicate with the interior of the can. Fitted within the tube 4 and extending concentrically therewith is a cylinder 5 forming part of a spraying device, said cylinder being closed at one end by a conical plug-receptacle or socket 6 secured in the end of the cylinder 5. Receptacle 6 has a portion 7 internally threaded for the reception of threads 8 formed on one end of a conical plug 9 which fits into the receptacle 6, and which, when unthreaded from the threads within the portion 7, is used as the operating handle of the sprayer. Plug 9 is secured on one

end of a piston rod 12 movable through the aperture 11 formed in the inner end or wall 10 of the conical receptacle 6.

Secured on the other end of the piston rod 12 is a piston 13 of the kind conventionally employed in spraying devices, said piston being mounted for reciprocation in the piston chamber or cylinder 5 by manipulation of the plug or operating handle 9, located at the bottom of the can body.

The upper end of the cylinder 5 is closed by a disc-shaped head plate 20 which is exposed at the top of the can body and is provided with the centrally located air spray opening 21. Located within the cylinder 5 is a partition 14 formed with a cupped portion 15 constituting a valve chamber within which a disc valve 17 is located. A cap 18 closes the valve chamber, said cap being formed with the opening 19 while the cupped portion 15 is provided with the opening 16. Through the mechanism thus far described, it will be apparent that when the plug 9 is unthreaded from the receptacle 6 and moved to and from the bottom of the can, piston 13 will cause an air stream to be intermittently issued from the air-spray opening 21 at the top of the can.

Located remotely from the air-spray opening in the top of the can, is a liquid-supply opening 23 communicating with the interior of the can. Surrounding said opening and upstanding from the top of the can is a cylindrical threaded spout 24. A siphon tube 22 attached to the top of the can by soldering or the like has one of its ends located adjacent to the spray opening 21 and has its other end communicating with the interior of the spout as indicated at 25.

The spout 24 is intended to receive a closure cap 26. Cap 26 is provided with a threaded plug portion 29, which, when the sprayer is to be maintained in inoperative position, is threaded down into the spout 24 as shown in Fig. 1, whereby the closed end 30 of said plug portion will cover the liquid-supply opening 23 as well as the end 25 of the siphon tube. Thus, communication between the liquid-supply opening 23 and the siphon tube 22 will be shut off and no liquid can be drawn through the siphon tube 22 should the piston 13 be reciprocated while the closure cap is in the position shown, or with the plug portion thereof located in the spout 24.

The closure cap 26 is also provided with a threaded cup-shaped portion 27 at its end opposite to that on which the plug portion is located. When it is desired to render the sprayer inoperative, the cup-shaped portion 27 of the 55

closure cap is threaded on the outside of the threads on the spout, as shown in Fig. 2, and said cup-shaped portion of the cap will then form the spout 24 into a liquid chamber into which liquid from the can may enter and from which it may be drawn through the siphon tube 22 when the piston 13 is reciprocated. The wall or partition 32 in the cap extends over and closes the end of the spout 24 when the cup-shaped end of the closure cap is in position on spout 24 and a suitable washer or gasket is interposed between said wall or partition and the end of the spout.

It may be desirable to utilize an absorbent material such as felt or the like in the spout, as shown at 28 in Fig. 2, when the parts are in the spraying position there shown, said absorbent tending to provide a uniform flow of liquid through the siphon tube. In such case, the felt 28 may be contained or stored in the cup-shaped portion of the cap during the periods when the parts are in non-spraying position, or in other words, when the plug portion 29 is inserted within the spout. By means of the reversible closure cap shown it will be apparent that the can may be sealed against leakage and evaporation when desired or placed in condition for spraying by merely reversing the position of the closure cap upon the spout.

When the can is sold, it is substantially full of the insecticide or other liquid adapted to be sprayed. At that time the closure cap 26 is in its closed position, namely, that wherein the plug portion 29 is threaded into the spout 24 as shown in Fig. 1. To place the device in condition for spraying merely requires the absorbent 28 to be placed in the spout 24 and the closure cap to be reversed or placed with its cup-shaped portion threaded on the outside of the threads on the spout. Upon reciprocation of the piston 13, the air blast emitted from air-spray opening 21 will draw moisture through siphon tube 22 and spray it in a finely diffused stream.

Various means may be utilized for holding the cylinder 5 within the tube 4, such means being arranged to either provide a permanent maintenance of cylinder 5 in tube 4 or permit the cylinder and associated elements to be bodily removed when desired. In other words, if desired, the sprayer, composed of cylinder 5 and its contents may be sold separately from the can and the purchaser, to at once convert the can into a spraying device, need only insert the cylinder into tube 4. These and other modifications may be made without departing from the spirit of the invention.

What I claim is:

1. A can for containing an insecticide or other liquid adapted to be sprayed, a spraying device having a cylinder located within the body of the can and having an end exposed out of one end of the can, said exposed end having an air spray opening, a piston in the cylinder and means for manually reciprocating the same, a liquid-supply opening in the end of the can wherein the spray opening is located, a siphon tube extending between the spray opening and the liquid-supply opening, a spout surrounding the liquid-supply opening, and a closure cap receivable in said spout to close the liquid-supply opening and shut off communication between the same and the siphon tube, said cap carrying an absorbent element interposed between one end of the siphon tube and the liquid-supply

opening when the closure cap is placed in reversed position in the spout.

2. A can for containing insecticide or other liquid adapted to be sprayed, a spraying device having a cylinder located within the body of the can and having an end exposed out of one end of the can, said exposed end being provided with an air-spray opening, a piston in the cylinder and means for manually reciprocating the same, a liquid-supply opening in the end of the can wherein the spray opening is located, said liquid-supply opening communicating with the interior of the can, a siphon tube having one end located adjacent the spray opening and its other end located adjacent the liquid-supply opening, a spout surrounding the liquid supply opening, a reversible closure cap for reception in either of two positions on the spout, a portion of the closure cap containing an absorbent material for receiving and holding liquid delivered to it through the air-supply opening when the closure member is in one of its positions on the spout.

3. A can for containing insecticide or other liquid adapted to be sprayed, a spraying device mounted within the can, said spraying device having a piston-reciprocating handle located at the bottom of the can and an air-spray opening at the top of the can, the top of the can having a liquid-supply opening, a siphon tube extending between the two openings, a spout encircling the liquid-supply opening, a closure cap having a closed end receivable in the spout for closing the liquid-supply opening, said closure cap being formed with a cup-shaped portion carrying an absorbent material for receiving liquid through the liquid-supply opening when the cap is in position with the cup-shaped portion fitted over the spout.

4. A can for containing a liquid to be sprayed, said can having a passage extending from one end of it to the other, the passage being open at its opposite ends, and adapted to removably receive the piston chamber of a spraying device, said piston chamber having an end provided with an air spray opening, said end being removable from the can with the piston chamber; a siphon tube located at one end of the can and having one of its ends located at one of the open ends of the passage near the air spray opening and being in position to co-operate with the spraying device disposed in the passage, the other end of the siphon tube communicating with the interior of the can.

5. A can containing insecticide or other liquid adapted to be sprayed, a spraying device mounted within the can, said spraying device having a piston-reciprocating handle located at one end of the can and an air spray opening located at the other end of the can, the same end of the can in which the air-spray opening is located being provided with a liquid-supply opening communicating with the interior of the can, a tubular spout surrounding the liquid-supply opening and projecting above the end of the can in which said opening is located, a closure member having a plug portion for reception within the spout to close the liquid-supply opening, said closure member being provided with a cup-shaped portion adapted to fit over the top of the spout to form the spout into a liquid chamber, and an absorbent element fitting the interior of the spout and retained therein by the cup-shaped portion of the closure member when said portion of the closure member is fitted over the spout.

6. A can containing insecticide or other liquid adapted to be sprayed, a spraying device located within and surrounded by the body of the can, said spraying device having an air-spray opening 5 located at one end of the can, said end of the can being also formed with a liquid-supply opening communicating with the interior of the can, a siphon tube extending between the two openings, a tubular spout extending around the liquid-supply opening and communicating with one end 10 of the siphon tube, an absorbent element held in the spout between the end of the siphon tube and the liquid-supply opening, and a closure cap removably fitted over the spout and holding the 15 absorbent element therein.

7. A can for containing insecticide or other liquid adapted to be sprayed, a spraying device mounted within the can, said spraying device having a piston-reciprocating handle located at 20 one end of the can and an air-spray opening at the other end of the can, one end of the can having a liquid-supply opening, a siphon tube having one end located adjacent to the air-spray opening and its other end located adjacent to 25 the liquid-supply opening, a closure cap provided with a closed end receivable over the liquid-supply opening to close the same, the opposite end of the cap being cupped to form a liquid-containing chamber around the liquid supply opening and the adjacent end of the siphon tube when the cap is placed over the opening with the cupped portion thereof directed toward the opening.

8. A can for containing an insecticide or other liquid adapted to be sprayed, including a spraying device having a cylinder located within the body of the can and extending from one end of the can to its other end, the end of the cylinder located at one end of the can having an air spray opening, the same end of the can having a 40

liquid-supply opening through which the liquid contents of the can pass, a spout surrounding the liquid-supply opening, a siphon tube located externally of the can and having one end located adjacent to the air spray opening and its other end extending into the spout and located therein adjacent to the liquid-supply opening, a removable closure member for fitment in the spout, said closure member containing an absorbent element, said closure member being constructed to fit the spout in either of two positions to either 5 shut off the liquid-supply opening or to hold the absorbent material within the spout over the liquid supply opening to enable said absorbent material to become liquid-saturated by the liquid 10 reaching the same through the liquid-supply opening. 15

9. A can for containing an insecticide or other liquid adapted to be sprayed, the top of the can being provided with a liquid-supply opening 20 through which the can contents may emanate, a spout surrounding said opening, a spraying device attached to the can body, the spraying device having an air-spray opening, a siphon tube having one end located adjacent to the air-spray 25 opening and its other end located in the spout and situated adjacent to the liquid-supply opening, a reversible closure cap for reception on the spout, said closure cap having a closed end receivable in the spout for closing the liquid-supply 30 opening and shutting off communication between the liquid-supply opening and the adjacent end of the siphon tube, said closure cap being formed with a cup-shaped portion at its other end receivable on the spout to form the 35 spout into a chamber in which liquid received through the liquid-supply opening may be contained when the cup-shaped end of the cap is fitted over the spout.

DAVID A. SPRIGINGS. 40
